UNITED STATES PATENT OFFICE.

CHARLES DE LUKACSEVICS, OF WEST NUTLEY, AND WILLIAM H. DANE, OF EAST ORANGE, NEW JERSEY, ASSIGNEES TO THE DANE MANUFACTURING COMPANY, OF NEWARK, NEW JERSEY, A CORPORATION OF NEW JERSEY.

SIPHON-HEAD.

1,199,671.

Specification of Letters Patent. Patented Sept. 26, 1916.

Application filed February 6, 1915. Serial No. 6,651.

To all whom it may concern:

Be it known that we, CHARLES DE LUKACSEVICS and WILLIAM H. DANE, citizens of the United States, residing at West Nutley and East Orange, respectively, in the county of Essex and State of New Jersey, have invented new and useful Improvements in Siphon-Heads, of which the following is a specification.

10 This invention relates to improvements in siphon heads and more particularly to an improvement in the jointure of the siphon head to the bottle neck, having for its principal object to provide a means of jointure 15 between the siphon head and the bottle neck which shall be strong, inconspicuous, substantially gas-tight, and readily effected and which shall prevent any accidental disassociation or relative movement of the siphon 20 head and the bottle, such as would tend to destroy or interfere with the gas-tight relation of said siphon head and bottle.

An embodiment of the invention is illustrated in the accompanying drawings, 25 wherein:—

Figure 1 is a sectional view showing an application of the siphon head to a bottle; Fig. 2 is a side elevation of the siphon head proper; Fig. 3 is a side elevation of the upper portion of the bottle and showing more particularly the details of the bottle neck; Fig. 4 is a top plan view of the bottle; and Fig. 5 is an elevation of the siphon head applied to a bottle.

35 Similar characters of reference designate corresponding parts throughout the several views.

The bottle, as A, has its neck provided with an upper reduced portion 1 formed 40 with relatively steep and preferably rounded external threads 2 which terminate adjacent the upper end of said neck and extend from a point adjacent an annular flat shoulder 3 formed, by virtue of the provision 45 of the reduced neck portion 1, adjacent the lower end of the same.

The siphon head has its lower portion formed as a socket 4 to engage over the bottle neck and provided with internal threads 5 for engagement with the threads 50 2. A gasket 6 is preferably interposed between the upper face of the bottle neck and the base of the socket. The socket 4 has a

flat under face 7 which confronts the flat face of the shoulder 3. The shoulder 3 and 55 the under face 7 of the socket 4 are provided at suitable intervals with grooves 8 which are preferably radially disposed and provide depressions in the flat confronting faces. These grooves 8 may be of any desired form. In Fig. 1 they are shown as of semi-circular form, in Figs. 2 and 3 as of V-shape form, and in Fig. 5 as of half-square form.

The extent and relation of the threads 2 65 and 5 are so selected that when the socket is screwed down upon the bottle neck sufficiently to exert sealing pressure upon the gasket 6, an annular space 9 will be left between the face 7 and the shoulder 3 and the 70 grooves 8, the intervals of which are the same in both of the confronting faces, will preferably be in registry, or substantially so. Lead in a soft or plastic state or some other equivalent agency is thereupon poured 75 into the space 9 until it completely fills the same and the registering grooves 8 which open into said space. The lead filling when it hardens forms an annular sealing key 10 between the under face of the socket 4 and 80 the shoulder 3 and by virtue of the provision of the grooves 8 takes a form wherein it provides radial locking ribs 11 which have secure engagement in said grooves and which, of course, extend across the space 9 85 and are integral with the major or body portion of the key 10 which has sealing engagement in said space 9. When the lead sealing key 10 with its locking ribs 11 has set, a gas-tight jointure is established 90 between the under face of the siphon head and the bottle neck and the efficiency of this jointure is permanently maintained since the ribs 11 prevent any relative turning movement of the siphon head and the bottle neck 95 such as would tend to interfere with the seal established by the gaskets 6 and 10.

The jointure between the siphon head and the bottle neck is advantageous, from the standpoint of appearance, in that it is neat 100 and inconspicuous and it is further advantageous in that the lead key does not project beyond the adjacent faces of the siphon head and bottle neck but is substantially flush therewith and, hence, being unexposed, 105 is not liable to intentional or accidental in-

jury and presents no temptations to persons of destructive tendencies.

While the locking and sealing key 10 effectively holds the siphon head against movement, and as just explained, is so arranged that it is not liable to intentional or accidental injury, said key may be readily removed by an authorized person whenever the occasion may require.

Having fully described our invention, we claim:—

1. In combination, a bottle having a threaded neck portion, a siphon head having a threaded portion to engage said neck portion, the bottle having a shoulder and the siphon head having a flat face confronting said shoulder, said shoulder and flat face having radial grooves and a locking and sealing element filling the space between said shoulder and said flat face and also filling said grooves.

2. In combination, a bottle having a threaded neck portion, a siphon head having a threaded portion to engage said neck portion, the bottle having a shoulder and the siphon head having a flat face confronting said shoulder, said shoulder and flat face having radial grooves and a locking and sealing metal key cast in the space between said shoulder and said flat face and extending into and filling said grooves.

3. In combination, a bottle having a threaded neck portion, a siphon head having a threaded portion to engage said neck portion, the bottle and the siphon head having confronting faces arranged in upper and lower relation and provided with grooves, and a sealing element filling the space between said confronting faces and also filling said grooves.

4. In combination, a bottle having a threaded neck portion, a siphon head having a threaded portion to engage said neck portion, the bottle and the siphon head having confronting faces arranged in upper and lower relation and provided with grooves, and a locking and sealing metal key cast in the space between said confronting faces and filling said grooves.

5. In combination, a bottle having the upper portion of its neck reduced and provided with external threads and having an annular external shoulder adjacent the base of said threads, a siphon head having an internally threaded socket to engage upon said threaded neck portion, the under face of said socket confronting said shoulder, a gasket interposed between the base of said socket and the upper end of the reduced neck portion, the under face of said socket and said shoulder being provided with radial grooves, and a locking and sealing element filling the space between said shoulder and the under face of said socket and also filling said grooves.

6. In combination, a bottle having the upper portion of its neck reduced and provided with external threads and having an annular external shoulder adjacent the base of said threads, a siphon head having an internally threaded socket to engage upon said threaded neck portion, the under face of said socket confronting said shoulder, a gasket interposed between the base of said socket and the upper end of the reduced neck portion, the under face of said socket and said shoulder being provided with radial grooves, and a locking and sealing metal key cast in the space between said shoulder and the under face of said socket and extending into and filling said grooves.

7. In combination, a bottle having the upper portion of its neck reduced and provided with external threads and having an annular external shoulder adjacent the base of said threads, a siphon head having an internally threaded socket to engage upon said threaded neck portion, the under face of said socket confronting said shoulder, the under face of said socket and said shoulder being provided with radial grooves, and a locking and sealing element filling the space between said shoulder and the under face of said socket and also filling said grooves, said element being flush with the adjacent external faces of said siphon head and said bottle.

8. In combination, a bottle having the upper portion of its neck reduced and provided with external threads and having an annular external shoulder adjacent the base of said threads, a siphon head having an internally threaded socket to engage upon said threaded neck portion, the under face of said socket confronting said shoulder, the under face of said socket and said shoulder being provided with radial grooves, and a locking and sealing metal key cast in the space between said shoulder and the under face of said socket and extending into and filling said grooves.

9. In combination, a bottle having the upper portion of its neck reduced and provided with external threads and having an external shoulder adjacent the base of said threads, a siphon head having an internally threaded socket to engage upon said threaded neck portion, the under face of said socket confronting said shoulder, the under face of said socket and said shoulder being provided with radial grooves, and a locking and sealing element having radial keys for engagement in said grooves.

10. In combination, a bottle having the upper portion of its neck reduced and provided with external threads and having an external shoulder adjacent the base of said threads, a siphon head having an internally threaded socket to engage upon said threaded neck portion, the under face of said socket confronting said shoulder, a gas-

cket interposed between the base of said socket and the upper end of the reduced neck portion, the under face of said socket and said shoulder being provided with radial grooves, and a locking and sealing element having radial keys for engagement in said grooves.

In testimony whereof we have hereunto

set our hands in presence of two subscribing witnesses.
